US0D1040367S

(12) **United States Design Patent** (10) **Patent No.:** **US D1,040,367 S**
(45) **Date of Patent:** **** Aug. 27, 2024**

(54) **SAMPLE COLLECTOR**

(71) Applicant: **Zhejiang Orient Gene Biotech Co., Ltd**, Zhejiang (CN)

(72) Inventor: **Jianqiu Fang**, Zhejiang (CN)

(73) Assignee: **ZHEJIANG ORIENT GENE BIOTECH CO., LTD**, Huzhou (CN)

(**) Term: **15 Years**

(21) Appl. No.: **29/774,038**

(22) Filed: **Mar. 12, 2021**

(30) **Foreign Application Priority Data**

Jan. 19, 2021 (CN) 202130037188.8

(57) **CLAIM**

I claim the ornamental design for a sample collector, as shown and described.

DESCRIPTION

FIG. 1 is a front view of a sample collector showing our design;

FIG. 2 is a back view of the sample collector;

FIG. 3 is a left side view of the sample collector;

FIG. 4 is a right side view of the sample collector;

FIG. 5 is a top view of the sample collector;

FIG. 6 is a bottom view of the sample collector;

FIG. 7 is a top, front perspective view of the sample collector; and,

FIG. 8 is a bottom, front perspective view of the sample collector.

1 Claim, 8 Drawing Sheets
